UNITED STATES PATENT OFFICE.

DAVID HENRY SAUNDERS, OF GLOUCESTER, MASSACHUSETTS, ASSIGNOR,
BY MESNE ASSIGNMENTS, OF FORTY-NINE ONE-HUNDREDTHS TO HANNA
V. P. MERCHANT, OF SAME PLACE.

BOX-HINGING MACHINE.

SPECIFICATION forming part of Letters Patent No. 623,834, dated April 25, 1899.

Application filed November 19, 1898. Serial No. 696,887. (No model.)

To all whom it may concern:

Be it known that I, DAVID HENRY SAUNDERS, a citizen of the United States, residing at Gloucester, in the county of Essex and State 5 of Massachusetts, have invented new and useful Improvements in Box-Hinging Machines, of which the following is a specification.

This invention relates to improvements in box-hinging machines for the purpose of automatically hinging wooden or other boxes or packages by means of metal wire staples, and it embodies in its construction automatic mechanism for feeding the wire from one or more reels, automatic mechanism for straightening, pointing, and cutting off the wire for the formation of the staples, means for frictionally holding the staple within the staple-forming die and carrier after the staple has been formed and until it is driven, automatic mechanism for driving the staples through the box and through the cover and clenching the same during the driving operation, automatic adjustable gage mechanism for locating and securing the box and the cover in position 25 for hinging previous to and during the hinging operation, and of other mechanism, as will hereinafter be more fully shown and described, reference being had to the accompanying drawings, wherein—

Figure 1 represents a top plan view of the machine, showing the wire-reels and their supports removed. Fig. 2 represents a side elevation of the machine. Fig. 3 represents a rear elevation of the machine, showing a portion of the frame or standard broken away. Fig. 4 represents a detail side elevation of one of the adjustable arms and its attached parts, showing the table, box, cover, and slide for the said arms in section. Fig. 5 represents a detail side elevation of one of said arms, showing the clamping device for holding the box and cover in position for hinging. Fig. 6 represents a detail top plan view of the vertically-movable box and cover supporting table. Fig. 7 represents a detail front elevation of the same. Fig. 8 represents a vertical cross-section on the line 8 8, shown in Figs. 6 and 7. Fig. 9 represents a detail vertical section of the staple forming and driving mechanism,

showing the formed staple within the female die or former before being forced into the receiver. Fig. 10 represents a detail vertical section showing the staple-blank in position between the male and female formers previous to forming the staple. Fig. 11 represents a detail top plan view of the female die or staple-former. Fig. 12 represents a rear view of the same. Fig. 13 represents a detail enlarged top plan view of the revoluble staple-receiver. Fig. 14 represents a side elevation 60 of the same. Fig. 15 represents a cross-section on the line 15 15, shown in Fig. 14. Fig. 16 represents a vertical cross-section of the male and female formers, showing the staple as formed. Fig. 17 represents a detail side 65 elevation of the carrier, showing it in its vertical position for receiving the staple and in two opposite inclined positions for driving the staples in the respective box and cover. Fig. 18 represents a detail interior view of 70 the rocking driver-yoke. Fig. 19 represents a top plan view of a portion of the hinged box and cover. Fig. 20 represents a rear view of the same. Fig. 21 represents a cross-section on the line 21 21, shown in Fig. 19. Fig. 22 represents a detail view of the staple. Fig. 23 represents a detail side elevation of 75 the cam for rocking the driver-yoke. Fig. 24 represents a detail side elevation of the cam for feeding the staple into the throat or receiver. Fig. 25 represents a detail side elevation of the cam for operating the combined box-clamp and clenching-block. Fig. 26 represents a detail side elevation of the cam for reciprocating the staple-formers in a horizontal direction. Fig. 27 represents a detail side elevation of the cam for operating the wire-feeding device. Fig. 28 represents a detail side elevation of the cam for operating the female die or former in a vertical direction. Fig. 29 represents a detail side elevation of the cam for oscillating the carrier, and Fig. 30 represents a detail top plan view of the throat or receiver oscillating mechanism.

Similar letters refer to similar parts wherever they occur on the different parts of the drawings.

In the drawings, A represents the frame or

standard, in bearings in which is journaled the rotary driving-shaft B, from which motion is conveyed to the different working parts, as will hereinafter be more fully described.

On the upper portion of the frame A is made a horizontal slide A', on which are longitudinally adjustable the arms C C, on which the mechanism for feeding, straightening, 10 and cutting off the wire is mounted, as well as the staple forming and driving mechanism, as will hereinafter be more fully shown and described.

In the drawings, Figs. 1, 2, 4, 5, 6, 7, and 8, 15 D represents the box, and D' represents the cover of the box, which are to be hinged together by the improved mechanism. The box and cover are clamped and held in position during the driving and clenching of the 20 staple-hinges, as follows: At the front of the frame A is located a vertically-movable angular table E E', composed of a horizontal portion E, upon which the cover of the box is supported, and a vertical portion E', suitably guided in ways on the vertical front portion 25 of the frame A. The said table E E' is automatically movable upward, preferably by means of a continuously-rotating cam-disk e, which actuates a lever e', pivoted at e'' and 30 having pivotally connected to its forward end a nut e³, containing an adjustable screw e⁴, the upper end of which bears against a rear projection e⁵ on the vertical table portion E', as shown in Figs. 2, 3, and 8. By this arrangement the angular table E E' is automatically movable upward, so as to cause the 35 box and cover to be held firmly against the forward lower portion C' of the arms C C, as shown in Figs. 2, 4, and 17, during the driving and clenching operation of the staples. The table E E' is automatically lowered by 40 its own gravity when the cam e ceases to act on the lever e', so as to permit the easy removal of the hinged box and cover and so as to enable the operator to place successive 45 ones in position for receiving the staple-hinges. The cam e is secured to a shaft e⁶, journaled in bearings in the frame A, and to it is secured a gear e⁷, meshing in a pinion e⁸, 50 secured to the driving-shaft B, as shown in Figs. 2 and 3.

On the horizontal table portion E is arranged a yielding gage F, against the rear portion of which is made to bear a preferable 55 leaf-spring F', which is secured to a block F'', adjustable on the table portion E, so as to compensate for variations in the width of the covers that are being hinged, as shown in Figs. 1, 2, 3, 4, and 5. A similar adjustable 60 and yielding device is used for the support of the box-body D, and it consists of brackets G G, preferably adjustable to and from each other in a slotted bar G', which is supported on a preferable leaf-spring G'', that is secured 65 to a block G³, adjustable on the table portion E', so as to compensate for variations in the

height of boxes that are being hinged, as shown in Figs. 2, 7, and 8.

f and f' are adjustable side guides on the respective table portions E and E', and they 70 serve as stops or guides against which the ends of the respective cover and box are placed, so as to locate said parts in their proper positions relative to the staple driving and clenching devices. 75

In bearings in the arms C C is journaled a shaft C'', which is set in rotary motion by means of the pinion e⁸ on the driving-shaft B, meshing in the teeth of an intermediate gear b, secured to a shaft b', journaled in the upper portion of the frame A. The gear b meshes in a gear C³, secured to the shaft C'', and in this manner a rotary motion is imparted to the said shaft C''. On said shaft C'' are splined a pair of longitudinally-adjustable sleeves C⁴, (one for each of the staple making and driving devices,) and to said sleeves are secured the various cams for operating the wire feeding and straightening, cutting-off, and pointing device, the staple-forming device, the staple-feeding device for the formed staples, the staple-driving device, the oscillating driver-carrier, the staple-carrying device for carrying the formed staple into position below the driver, and the box and cover clamping device, as will hereinafter be more fully shown and described. 80 85 90 95

The clamping device for automatically clamping the rear side of the box against the vertical portion E' of the angular table and the cover against its yielding gage is constructed as follows:

On the sleeve C⁴ are secured a pair of cams II II, (one for each staple-driving device.) Each such cam during its rotation comes in contact with the rear end of a link II', that is pivoted at its rear end to a rocking lever II'', which latter is pivoted at its lower end on an adjustable fulcrum II^{3X}, secured to the arm C, as shown in Figs. 1, 5, and 25. The forward end of the link II' is pivoted to the upper end of the clamping-lever II³, which is pivoted to the forward end of a longitudinally-adjustable bar II⁴, that is adjustably secured to the arm C at h⁴ for the purpose of compensating 110 for variations in the thickness of the stock of which the boxes are made. This bar II⁴ is supported intermediate its ends on the pin II^{3X}, disposed at right angles thereto, as seen in Fig. 5. Within the inner face of the 115 clamping-lever II³ is secured a preferably steel-hardened clenching-block h³, against which the pointed ends of the staple driven through the box-body are clenched during the staple-driving operation. 120 125

f'' f'' are clenching-blocks arranged in a groove f³ in the horizontal table portion E, against which the pointed ends of the staples driven through the cover are clenched during the driving operation. The clenching-blocks 130 f'' f'' are adjustable to and from each other, so as to be located corresponding in positions

relative to the staple-driving devices, which are likewise adjustable to and from each other, according to the distance apart in which the staples are desired to be driven, as will 5 hereinafter be described.

h" is a spring which actuates the lever *H*", so as to automatically release the clamping-lever *H*³ as soon as the cam *H* ceases to act on said lever *H*", as shown in Fig. 5.

10 The automatic mechanism for feeding, straightening, pointing, and cutting off the wire preparatory to forming the staples is carried out as follows: Each of the staple forming and driving devices receives its wire 15 *i* from a reel *I*, from which the wire is intermittently carried by the feed device partially around a loosely-rotating grooved wheel *I*', and from the latter between a pair of straightening-rollers *I*" *I*³, one or both of which may 20 be adjustable, although in practice it may only be required to make one of said rollers adjustable, as shown in Figs. 2 and 4. The wire is fed, cut off to the required length, and pointed by means of a pair of feed, cutting, 25 and pointing levers *I*⁴ *I*⁴, pivoted at *i*⁴ *i*⁴ to a slide *I*⁵, which is set in a reciprocating motion, preferably by means of a rod *I*⁶, pivotally connected to said slide and actuated by a track-cam *I*⁷, secured to the rotary sleeve 30 *C*⁴, as shown in Figs. 1, 2, 4, and 27. The levers *I*⁴ *I*⁴ are caused to impinge on opposite sides of the wire by the influence of springs *i*⁵ *i*⁵ when the slide *I*⁵ is moved in the direction of the arrow shown in Figs. 2 and 4. 35 When the slide *I*⁵ is moved in an opposite direction, the said levers *I*⁴ *I*⁴ are released and made to slide freely back on the wire, which during such backward motion of the slide *I*⁵ is held stationary between a fixed block *I*⁸ 40 and a spring-pressed brake *I*⁹, as shown in Figs. 2 and 4. The wire is cut off and pointed as the slide *I*⁵ approaches the forward end of its stroke by the levers *I*⁴ *I*⁴ coming in contact with stops *i*⁶ *i*⁶, adjustably secured to the 45 arm *C*, by which the said levers are caused to rock backward sufficiently to bring their abutting cutting jaws or surfaces in contact, by which the wire is additionally pinched sufficiently to point and sever it at the desired 50 place, according to the length of staple required. By adjusting the position of the stops *i*⁶ *i*⁶ the length of the staple-blanks are regulated according to the thickness of the stock of which the boxes to be hinged are 55 made.

For the purpose of regulating the amount of feed of the wire *I* secure in an adjustable manner to the arm *C* a pair of blocks *I*¹⁰ *I*¹⁰, which during the return motion of the slide 60 *I*⁵ come in contact with the upper ends of the levers *I*⁴ *I*⁴, causing them to be released from gripping the wire and held so until the said levers are released from contact with said blocks *I*¹⁰ *I*¹⁰ during the forward motion 65 of the feed device.

The staple forming and driving device is carried out as follows:

In guides in the forward end of each arm *C* are arranged a female die or former *K* and a male former *K*'. The female die or former has a 70 vertical perforation *k* for receiving the driver-bar, and at two opposite sides of such perforation are made longitudinal recesses *k*' *k*' for receiving the sides of the staple during the forming operation, as shown in Figs. 5, 9, 10, 75 11, 12, and 16.

K" is a vertically-movable plunger guided in ways on the arm *C*, and to it is imparted a vertical reciprocating motion by means of a lever *K*³, pivoted at *k*³ to the arm *C* and operated in one direction to force the plunger down by means of a cam *K*⁴, secured to the rotary shaft-sleeve *C*⁴, and in the opposite direction by the influence of a spring *k*⁴, as shown in Figs. 2, 4, 5, and 28. The forward end of the 85 lever *K*³ is pivotally connected to the upper end of the plunger *K*"', as shown. The lower end of said plunger *K*"' is connected to the female die or former *K* in such a manner as to permit the female die *K* to be laterally movable relative to said plunger, for a purpose as 90 will hereinafter be described.

A lateral reciprocating motion is given to the male former by a lever *K*⁵, pivoted at *k*⁵ to the frame *C* and operated in one direction 95 by a cam *K*⁶, secured to the sleeve *C*⁴, and in the opposite direction preferably by the influence of a suitable spring.

To the male former *K*' is secured a pin or projection *k*⁶, adapted to be received in slots *k*⁷ in the wings of the female die *K*, as shown in Figs. 9, 10, and 11. Said slots are vertical in their lower ends and inclined in their upper ends, as shown, so as to permit the female die to descend during a part of its stroke to 105 form the staple *i*⁷ by bending it over the male former without causing such female die to move horizontally, and during such staple-forming operation the projection *k*⁶ on the male former is received in the vertical lower 110 portions of the slots *k*' *k*⁷ in the wings of the female die. During the further descent of the female die (after the formation of the staple) it is caused to move longitudinally forward 115 relative to the male former by the action of the pin *k*⁶ on the male former passing into the upper inclined portion of the slots *k*⁷ in the female die or former, and this is done for the purpose of carrying the formed staple *i*⁷ clear of the male former, so as to allow the driver-bar *L* to drive the staple *i*⁷ when placed in 120 proper position for driving without coming in contact with the male former. After the female die or former has been thus moved in advance of the male former both are moved 125 horizontally by the lever *K*⁵, so as to bring the staple *i*⁷ centrally below the driver-bar *L*, as shown in Fig. 9. The cut-off and pointed wire is automatically fed between the upper part of the male former and lower part of the 130 female former, as shown in Fig. 10, after which the female former is caused to descend, so as to bend and shape the staple over the sides of the male former and causing the prongs of

said staple to be held frictionally within the female die or former after the male former has been withdrawn.

Instead of depending on the expanded 5 prongs of the staple to retain the latter frictionally within the female die or former I may make use of one or a pair of friction-springs of the kind usually employed in nail-driving devices.

10 L' is the rocking carrier, containing the driver-bar L . Said carrier has at its lower rear portion a T-headed projection L'' , which during the rocking motion of said carrier is guided in a curved slot C^5 of corresponding size and 15 shape in the sides of the lower forward end of the arm C , as shown in Figs. 2, 4, 9, 10, and 17. An intermittent rocking motion is automatically imparted to the carrier L' by means of a link L^3 , pivotally connected to the carrier 20 and actuated, preferably, by a grooved cam L^4 on the rotary sleeve C^4 , as shown in Figs. 1, 2, 4, 5, 9, 17, and 29, and by such or equivalent mechanism the said carrier is rocked from its position shown in full lines in Figs. 25 9 and 17 to either of its inclined driving positions shown in full lines in Figs. 2 and 4 and in dotted lines in Fig. 17, for a purpose as will hereinafter be more fully described.

Within the lower end of the rocking carrier L' is journaled the throat or receiver L^5 , into which the formed staple is forced by the driver-bar L at the time the carrier is held in its central vertical position. The carrier L' is provided with a longitudinal slot l' , in which 35 the driver-block l is longitudinally movable, and to said driver-block is secured the driver-bar L , as shown in Figs. 2, 4, 9, and 17.

In a bearing C^6 , forming a part of the forward end of the arm C , is journaled a pin or 40 shaft l^6 , to which is secured the rocking driver-yoke, having downwardly-projecting inclined driver-arms $L^7 L^7$, as shown. In one piece with said arms is preferably made an upwardly-projecting lever L^8 , to which an intermittent rocking motion is conveyed by means 45 of a preferably-grooved cam l^8 , secured to the rotary sleeve C^4 , and an intermediate link L^9 , pivotally connected to the lever L^8 , as shown.

$l^7 l^7$ are longitudinal grooves or ways on the 50 inclined arms $L^7 L^7$, in which is guided a roll L^{10} , mounted on a pin l^{10} , secured to or made integral with the driver-block l , as shown in Fig. 18, by which arrangement the driver-block and driver-bar are caused to ascend in 55 the carrier during the rocking motion of the latter from its inclined to its central position, so as to bring the lower end of the driver-bar above the upper end of the staple previously formed, and said grooves also serve to automatically depress the driver-bar when the latter is moved from its vertical to its opposite inclined position, so as place such driver-bar in position for driving.

Between the inclined rocker-arms $L^7 L^7$ is 60 arranged a downward projection L^{12} , having a groove or way l^{12} , in which is longitudinally movable the spring-pressed block L^{13} , actu-

ated by a compressible spring l^{13} , which serves to hold the block L^{13} in its upper position when not depressed by the pin and roll on the driver-block. 70

While the driver-yoke is held in its midway position (shown in Figs. 2, 4, 5, 9, 10, and 18) and while the formed staple is being held within the female die or former K , as shown 75 in Figs. 9 and 16, the driver-bar L is automatically depressed, so as to push the staple out of the said female die or former into the receiver L^5 , and this is accomplished by means of a rocking lever M , pivoted at k^3 and actuated by a cam m , secured to the rotary sleeve C^4 . The forward end of said lever M during its depression comes in contact with a pin and roll or pin L^{14} on the driver-block, causing the latter and its driver-bar to be momentarily depressed for the purpose stated and immediately returned to its highest position by the influence of the spring l^{13} . The carrier L' is then swung to one of its inclined positions, and while held in such position the 80 driver-yoke is rocked sufficiently to cause the driver-bar to descend and drive the staple through the cover and box alternately and 85 clench it against the respective clenching-surfaces. 90

95 In hinging boxes by means of wire staples it is essential that one of such staples should be turned at about a right angle to the other, so as to cause such staples to be properly interlocked for the formation of the hinge, and 100 for this purpose I employ an automatic device for turning the staple-receiver L^5 about a quarter of a revolution at or about the time the carrier L' moves from its vertical to its opposite rocking position, and such turning 105 mechanism is preferably constructed as follows: On the side of the staple receiver or throat L^5 is a pin or projection N , which as the carrier and receiver are moved from the central to one of its inclined positions is 110 caused to enter a recess n in the arm C , by which the said throat or receiver is caused to rotate about a fourth of a revolution for the purpose stated. A coiled spring N' , attached in one end to the said throat or receiver and 115 to the carrier L' in its opposite end, serves to hold said pin or projection N in contact with the arm C during the rocking movement of the carrier L' and to compel said pin to enter 120 said recess during the turning operation, as 125 shown in Figs. 9, 13, 14, 15, and 30.

130 It will be noticed by reference to Fig. 22 that the prongs of the staple i^7 after the staple is formed by the male and female dies or formers are left somewhat expanded at their free ends, and by such arrangement the staple is caused to be frictionally retained in position both within the female die as well as within the throat or receiver before being forced out of such devices by the driver-bar, thus preventing the said staple from dropping out of said die and receiver until positively actuated by the descent of the driver-bar.

The operation of the device is as follows: The operator places a box-cover D' on the horizontal table portion E against the yielding-gage F and places the box D upon the yielding brackets G G, after which the operator starts the machine, causing the automatic clamping devices to force the box in close contact with the edge of the cover and to confine the upper portion of the box and the cover between the vertically-movable table and under side of the arm C in proper position for receiving the staples, as shown in Figs. 2, 4, 9, 10, and 17. During a previous partial rotation of the driving-shaft the wire has been fed, straightened, pointed, cut, and formed into a staple located in position, placed into the throat or receiver, and the carrier rocked to its position for driving the staple through the cover and clenching the same. The driver-yoke is then automatically rocked for the purpose of causing the driver-bar to descend through the receiver and drive the staple through the cover and clench the ends against the clenching-blocks on the horizontal part of the box and cover supporting table. While the box and cover are still clamped in position, a subsequent portion of the wire is automatically fed, straightened, cut off, and pointed and a new staple formed, and during such operation the carrier is automatically rocked from its inclined driving position to its central vertical position, causing the lower end of the driver-bar to rise above the top of the staple just formed and placed into position below it, after which the driver-bar is caused to descend for the purpose of forcing the staple out of the female die and into the receiver, after which the carrier is automatically rocked to its opposite driving position, and during such rocking motion the throat or receiver containing the staple is automatically turned about a fourth of a revolution, after which the driver-yoke is rocked, so as to cause the driver-bar to descend to drive such second staple through the box and clench the same against the block in the clamping-lever and in such a manner as to be interlocked with the previously-driven staple. The clamping-lever is then automatically released and the table lowered to its lowest position, enabling the operator to remove the now hinged box and cover and to replace such with a fresh box and cover to be hinged as before. During the interval of the release of the clamping device, the removal of the hinged box and cover, and the replacing of such with a subsequent box and cover to be hinged a new staple has been automatically cut off, pointed, formed, and placed in position for driving and the carrier automatically rocked into driving position, and so on during the operation of the machine.

Having thus fully described the nature, construction, and operation of my invention, I wish to secure by Letters Patent and claim—

1. In a box-hinging machine, in combination, one or more intermittently-actuated sta-

ple-forming devices and intermittently-oscillating staple-driving devices, an intermittent wire feeding, straightening, pointing and cutting device and an automatic box and cover supporting and clamping device, substantially as and for the purpose set forth. 70

2. In a box-hinging machine, in combination, one or more intermittently-actuated staple-forming devices and intermittently-oscillating staple-driving devices and means for automatically feeding the staple-blank to the forming and driving device, substantially as and for the purpose set forth. 75 80

3. In a box-hinging device, in combination, an intermittent wire-feeding device, a wire cutting pointing and straightening device an intermittently-actuated staple-forming device and a staple-driving device which by its oscillation presents as well as drives the successive staples in different directions, substantially as described. 85

4. In a box-hinging machine, in combination, an intermittent combined wire feeding, straightening, cutting and pointing device, staple forming and driving device, and an automatically-actuated box and cover support or table adapted to be automatically moved to and from the staple-driving device 90 95 and means for turning one staple at right angles to its fellow, substantially as and for the purpose set forth.

5. In a box-hinging machine, in combination, an intermittent combined wire feeding, straightening, cutting and pointing device, a staple forming and driving device, means for turning one staple at right angles to its fellow, an automatically-operated box and cover table or support, means for automatically moving the same to and from the staple-driving device and automatic means for clamping and holding the box and cover in position during the driving and clenching operation, substantially as and for the purpose set forth. 100 105 110

6. In a box-hinging machine, in combination, an intermittent wire feeding, cutting and pointing mechanism, a staple-forming mechanism and an oscillating staple-driving mechanism adapted to intermittently drive the staples at about a right angle respectively through the box and through the cover and clench said staples, substantially as and for the purpose set forth. 115 120

7. In a box-hinging machine, in combination, a staple-forming and an intermittently-oscillating driving device which by its oscillation presents as well as drives the successive staples in different directions, a wire feeding pointing and cutting device, consisting of a reciprocating slide having pivotally connected thereto a pair of feed cutting and pointing levers adjustable devices for regulating the amount of feed and place of cut-off, 125 and an automatic brake device adapted to hold the wire stationary during the return motion of the wire-feed device, substantially as and for the purpose set forth. 130

8. In a box-hinging machine, in combination, an intermittent wire feeding, cutting-off and pointing device, a staple-forming device and an oscillating staple-driving device adapted to intermittently drive the staples through the box and cover at substantially right angles to each other, as and for the purpose set forth. 75
9. In a box-hinging machine, in combination, a staple forming and driving device and an automatic, vertically-movable table or box and cover support and spring-pressed and adjustable gages thereon for placing the box and cover in proper position relative to the staple-driving device and clamping devices having a positive action counter to that of the spring-gages to bring the work into its proper position substantially as specified. 15
10. In a box-hinging machine a rotary driving-shaft, a pair of sleeves splined on said shaft and longitudinally adjustable thereon, a pair of laterally-adjustable arms each having connected to it a wire-feed straightening, pointing and cutting device, a staple-forming and intermittently-oscillating driving device which by its oscillation presents as well as drives the successive staples in different directions through the box and cover, an automatic clamping device for clamping the box and cover in position for receiving the staples and intermediate devices between the said sleeves and the said wire-feed, straightening, pointing and cutting device, and between said sleeves and the staple forming and driving devices, as set forth. 30
11. In a box-hinging machine, in combination, an intermittent wire feeding, straightening, cutting and pointing device, a staple forming and driving device; an automatically, vertically-movable box and cover support having a clenching-die on its upper portion and an automatic clamping device having a similar clenching-die, substantially as and for the purpose set forth. 40
12. In a box-hinging machine, in combination, a staple-forming device consisting of a male and female former, and an oscillating staple-receiver located beneath the driving device and mounted to oscillate around its axis and means for frictionally holding the staple within said female former and receiver, substantially as specified. 50
13. In a box-hinging machine, in combination, a staple-forming device, an oscillating driver-yoke mounted to oscillate around its own axis and a driver-bar actuated by the yoke for driving the staples alternately through the box and cover and a receiver mounted to oscillate around its axis, substantially as and for the purpose set forth. 55
14. In a box-hinging machine, in combination, a staple-forming device, an oscillating driver-yoke, a driver actuated by the latter and an automatically-actuated oscillating staple-receiver mounted to oscillate upon its own axis for the purpose of alternately driving the staples at right angles respectively 65
- through the box and cover, substantially as specified. 70
15. In a box-hinging machine, in combination, a staple-forming device, an oscillating driver-yoke adapted to actuate the driver-bar, and an oscillating driver-carrier for the purpose of alternately driving the staples through the box and cover, substantially as specified. 75
16. In a box-hinging machine, in combination, a staple-forming device, mechanism for automatically placing the formed staple below the driver-bar, a receiver mounted to oscillate on its own axis below the driving device, mechanism for locating the formed staple into the receiver and for driving said staple out of the receiver into the box and cover, substantially as and for the purpose set forth. 80
17. In a box-hinging machine, the herein-described staple forming and placing mechanism consisting of a vertically and horizontally movable female former and a horizontally-movable male former, and automatic mechanism as described for causing the female former to descend relative to the male former for forming the staple, mechanism for automatically moving the female former laterally relative to the male former so as to release the staple from the latter, and automatic mechanism for moving the male and female formers in a lateral direction for the purpose of causing the staple to be located below the driver-bar, substantially as and for the purpose set forth. 90
18. In a box-hinging machine, in combination, the following automatically-actuated elements, viz: an intermittent wire feeding and straightening device, a wire-cutting-off device, a staple-forming device, a rocking driver-carrier adapted to alternately drive the staples at right angles through the box and cover, a box and cover support, and a driving device, substantially as and for the purpose set forth. 95
19. In a box-hinging machine, in combination, the following automatically-actuated elements, viz: an intermittent wire feeding, cutting, pointing and staple-forming device, a driver device for alternately driving the staples interlocking through the box and cover, a vertically-movable box and cover support and a clamping device for securing the box and cover in driving positions, substantially as and for the purpose set forth. 105
20. In a box-hinging machine, the following combined automatically-actuated elements, viz: a wire-staple-forming device, a placing device for locating the staple in position for driving, a rocking carrier for alternately placing the staples to be driven through the box and cover, an oscillating receiver for turning one staple at right angles to its fellow, a driving device and a clamping device, substantially as and for the purpose set forth. 115
21. In a box-hinging device, in combination an intermittent wire-feeding device, a wire cutting pointing and straightening device an 120
- 130

intermittently-actuated staple-forming device and a staple-driving device which by its oscillation presents as well as drives the successive staples in different directions and automatic mechanism for holding the box and cover in position for driving and clenching the staples substantially as described.

In testimony whereof I have hereunto set my hand in presence of two subscribing witnesses.

DAVID HENRY SAUNDERS.
